PHASE OR FREQUENCY MODULATED
TRANSMITTERGeorge Lindley Usselman, Port Jefferson, N. Y.,
assignor to Radio Corporation of America, a
corporation of Delaware

Application February 23, 1937, Serial No. 126,954

9 Claims. (Cl. 179—171)

This invention discloses a method of and means for phase or frequency modulating high frequency wave energy. This is accomplished by producing a reactive effect and varying the said reactive effect in accordance with a signal. In a practical embodiment the reactance may constitute the anode tuned circuit of one stage of a transmitter.

In this system substantially no amplitude modulation is generated during the process of phase 10 or frequency modulation.

In describing my invention reference will be made to the attached drawings wherein

Figures 1 and 4 are basic circuit diagrams illustrating the manner in which the reactive effects 15 are obtained in a single stage and in a push-pull stage respectively, and varied at signal frequency;

Figures 2 and 3 show two single tube stage modifications of my novel phase or frequency modulation system; while

Figure 5 illustrates one push-pull embodiment 20 of my signalling system.

My invention as illustrated in Figure 2 comprises an exciter E, phase modulation elements or means A—B—C—F, audio modulation frequency 25 amplifier or modulator elements D—D₁—H—T₁ and/or frequency multiplier I and antenna J.

More in detail the source of wave energy of the 30 desired frequency at E supplies wave energy by way of coupling and blocking condenser 1 to the grid 4 of tube F. Operating bias for grid 4 is supplied from source 6 by way of leak resistance 2. F may be of the screen grid type as shown and 35 may have a screen grid 8 connected to a point on source 10. The anode 12 of F is connected to a tuned circuit or reactive network comprising inductance C, tuning capacities A—B in series in shunt to C and a choke inductance L shunting B. Choke L is provided to supply plate current to tube D. The wave energy transferred to F and 40 from F to the network A—B—C as modified therein is impressed by way of coupling and blocking condenser 14 to a unit I which may include as desired, amplifiers, frequency multipliers, and amplitude limiters. The output from the 45 unit I is impressed on an antenna system J. The antenna system J may of course be replaced by transmission lines or any other load circuit. A point on the inductance C is connected to the anode 18 of a modulator tube D', while a point between condensers A and B is connected to the 50 anode 20 of a modulator tube D. The control grids 22, 24 of tubes D₁ and D respectively, are connected to the secondary winding 28 of a transformer T₁, the primary of which is connected 55 with any source of controlling potentials H. The

controlling potentials at H may be of tone frequency or may be characteristic of voice signals. Bypass or blocking condensers are shown marked as X. The purposes of other parts of the transmitter are apparent to those skilled in the art. 5

The operation of this invention is as follows, and is based on two fundamental facts. Given a parallel circuit consisting of a capacity and an inductance tuned to resonance at a given frequency, it becomes effectively a pure resistance 10 and if a variable resistance or impedance is connected or tapped across a part of either leg or branch of the parallel circuit the tuned circuit becomes a variable impedance containing a variable reactive component. The second fact is 15 that alternating current in passing through an impedance element containing reactance will have its phase displaced. In the present disclosure A—B—C of Figures 1 and 2 and A—B—C and A'—B'—C' of Figures 4 and 5 are the tuned 20 circuit described above while the shunting resistances or impedances or one of the same of all figures are the variable resistances or impedances described above.

In Figure 1 we have a parallel tuned circuit 25 consisting of the inductive branch C and the capacitive branch A—B. Across a portion of the inductive branch we have connected in shunt variable resistor D'. This resistance D' represents the resistance of tube D' of Figure 2. Also across 30 a portion of the capacitive branch A—B we have connected in shunt variable resistor D. This resistor D represents the resistance of tube D of Figure 2.

The operation of the invention may be more 35 clearly understood by first referring to Figure 1 for explaining some of the principles. To begin, assume capacitance A—B and inductance C to be tuned to resonance at some desired frequency (f) so that the impedance between points P₁ and P₂ is substantially pure resistance. Now, if we tap variable resistor D' across a part of inductance C, the circuit will tune at a higher frequency and the impedance between points P₁ and P₂ will have an inductive reactance component at 45 frequency (f). If we remove resistor D' and instead tap variable resistor D across capacitor B which is a portion of the total capacitive branch 50 of the circuit, the circuit will tune at a lower frequency and the impedance between points P₁ and P₂ will have a capacitive reactance component at frequency (f).

Now, returning to the drawings, if we connect both resistors D' and D as mentioned above and as shown in Figure 1 assuming a balanced condi- 55

tion on each side of the tuned circuit, the impedance between points P_1 and P_2 will again be substantially pure resistance. If we vary the value of resistors D' and D cophasally or in the same direction, the effective resistance between points P_1 and P_2 will change in value but there will be no reactive component. If we vary the value of resistors D' and D differentially, that is in opposite directions, the effective resistance component between points P_1 and P_2 will remain substantially constant but the reactive component will swing or oscillate from capacitive to inductive reactance and vice versa depending upon the values of resistors D' and D .

15 Applying the above principles to a circuit as shown in Figure 2 modulator tubes D' and D fulfill the purpose of resistors D' and D in Figure 1. The anode current in these tubes constitutes the resistance which is varied by varying the amount of anode current. This is done differentially through transformer T from audio signal source H as shown in Figure 2. It will be noted that anode current for tube D' is drawn from tank coil C and that anode current for tube D is supplied through choke L which is connected to one end of coil C as shown.

As has been explained above, a change in the reactance of the tuned anode circuit such as $A-B-C$, changes the phase of the electrical oscillations in it as compared to the grid excitation oscillation. Therefore, if tubes D and D' are modulated differentially according to the signal the phase of the energy in the tank circuit of transmitter tube F will be phase modulated according to the signal. This phase modulated energy will also be substantially free from amplitude modulation for as explained in connection with Figure 1, the resistive component between P_1 and P_2 remains substantially constant.

40 This phase modulated energy may be repeated, amplified, limited in amplitude, and/or multiplied in frequency in other stages such as I in Figure 2 before it is radiated by antenna J .

Other modifications of this invention could be suggested such as the one shown in Figure 3. In this case the modulated stage is an oscillator, having a tuned grid circuit 30 coupled by a condenser N to the parallel circuit $A-B-C$ connected to the anode. The grid circuit 30 is shown as a standard tuned circuit. Oscillations are produced by virtue of interelectrode capacity and/or feedback through N . The remaining portions of this oscillator which is phase or frequency modulated will be understood when considered in the light of the foregoing description of the previous figures. If a crystal be substituted for grid circuit 30 the transmitter will deliver a phase modulated signal. The same could be said if grid circuit 30 is a resonant line. However, if a high power factor or high loss grid circuit such as shown at 30 in Figure 3 is used the transmitter will deliver mostly a frequency modulated carrier signal. This because there is little stored energy in circuit 30 and therefore the frequency of excitation energy in circuit 30 will follow that of the tank circuit A, B and C . In other words, the stability of the grid circuit 30 is low and will follow the frequency of the feedback energy to produce in the oscillator frequency modulated waves. The phase and frequency modulated energy from the oscillator may be repeated, amplified and/or multiplied in frequency in one or more stages such as I before being radiated by antenna J . The transmitters shown in Figure

3 and suggested above would also be substantially free from amplitude modulation.

Referring to Figures 2 and 3 in order to get balanced modulator action, for proper operation to prevent generation of amplitude modulation, 5 capacitors A and B should be adjusted so that the action $B-D-L$ will be equal in magnitude to the action of D' and the tapped portion of coil C . Obviously, the total capacity of capacitors A and C should be kept constant except the adjustment 10 necessary for tuning. In other words, if capacitor B is decreased by a certain amount then capacitor A should be increased by the same amount and vice versa to maintain the tuned condition in tank circuit A, B and C . 15

While I have illustrated in the preceding figures the application of my novel phase modulating scheme to single ended or single tube stages it will be realized that the same is also applicable to double ended or push-pull stages. When the 20 invention is applied to double ended or push-pull stages the fundamental circuit illustrating the manner in which the reactive effects are produced and changed at signal frequency will be as illustrated in Figure 4. In this fundamental diagram 25 as in Figure 1, A and B represent capacitive reactances. D represents a variable resistor in shunt to B while D' represents an additional variable resistor connected in shunt to a portion of C . Here, since a push-pull effect is involved, 30 additional inductance C' and additional condensers $A' B' A'$ are used. Thus, we have condensers $A B B' A'$ in series in shunt to C and C' with a choking inductance L_2 connecting a point between B' and B to a point between C and C' 35 and to ground. The variable resistances D and D' of Figure 1 are supplemented by additional similar variable resistances $2D$ and $2D'$.

While it is believed the push-pull modification as illustrated in Figures 4 and 5 will be readily 40 understood by those skilled in the art, the operation thereof will be set forth here, even though it is in part a repetition of the statement of operation of the modifications shown in Figures 1, 2, and 3. 45

To more or less repeat my previous disclosure, assume capacitance A, B, A' and B' , and inductance E to be tuned to resonance so that the impedance between points P_1 and P_2 is substantially pure resistance for alternating currents. 50 If we tap variable resistors D' and $2D'$ across a part of inductance C as shown, the circuit will tune at a higher frequency and the impedance between points P_1 and P_2 will have an inductive reactive component. If we remove resistors D' and $2D'$ and instead tap variable resistors D and $2D$ across capacitors B and B' which is a portion of the total capacitive branch of the circuit, as shown the circuit will tune at a lower frequency and the impedance between points 60 P_1 and P_2 will have a capacitive reactance component.

Now, if we connect variable resistors D and $2D$ and D' and $2D'$ as mentioned above and as shown in Figure 4, assuming a balanced condition one 65 each side of the tuned circuit, right and left and also above and below the grounded central point, the impedance between points P_1 and P_2 will again be substantially pure resistance. If we vary the value of these resistors cophasally or in the same 70 direction, the effective resistance between points P_1 and P_2 will change in value but there will be no reactive component. If we vary the value of resistors $D-2D$ and $D'-2D'$ differentially, that is, $D-2D$ in opposite direction from $D'-2D'$, the 75

effective resistance component between points P_1 and P_2 will remain substantially constant but the reactive component will swing or oscillate from capacitive to inductive reactance and vice-versa depending upon the values of resistors D — $2D$ and D' — $2D'$.

In the modification shown in Figure 5 as in the prior figures, E represents any source of wave energy to be modulated. This source of wave energy is connected by coupling condensers I to the control grids of a pair of tubes F , F' , the anodes of which are connected to the reactive network A — B — C A' — B' — C' . Here, as in the prior modification the reactance of the network is controlled by modulator tubes D and D' connected in phase opposition between a source of modulating potentials H and the said network. The tubes D and D' are in modification of any appropriate type having two anodes. For example, they may be tubes of the type RCA-19 and RCA-79 or RCA-53. In operation the grids may be tied together to operate in phase as a single grid. The anode to cathode impedances of D' represent resistors D' and $2D'$ and are varied in phase. The anode to cathode resistances of D represent resistors D and $2D$ and are varied in phase.

Applying the above principles to a push-pull circuit as shown in Figure 5, modulator tube D with anodes 40 and 42 fulfill the purpose of resistors D and $2D$, while modulator tube D' with anodes 44 and 46 fulfill the purpose of resistors D' and $2D'$. The anode current in tubes D and D' constitute the resistances which are varied by varying the amount of anode current. This is done differentially through transformer T from signal source A acting on the grids of tubes D and D' as shown in Figure 5. It will be noted that the anodes 44 and 46 of tube D' draw current from tank coil CC' and that the anodes 40 and 42 of tube D are supplied with current from choke coil L which is connected to the center of tank coil CC' as shown through choke coil L_2 . It will also be noted that the anodes 40 and 42 of tube D are connected across equal impedances on each side of the neutral point of the tank circuit condensers and that the anodes 44 and 46 of tube D' are connected also across equal impedances each side of the neutral or central point of the tank circuit coil as shown in Figure 5. This is to insure equal or balanced modulator action each side of the push-pull circuit for the prevention of amplitude modulations.

It has been explained hereinbefore that a change in the reactance of the tuned anode circuit, such as A , B , C , A' , B' , C' changes the phase of the electrical oscillations in it as compared with the grid excitation oscillations. Therefore, if tubes D and D' are modulated differentially according to the signal the phase of the carrier energy in the tank circuit of the transmitter stage will be phase modulated according to the signal. This phase modulated energy should be substantially free from amplitude and other spurious modulation for reasons explained in connection with Figure 1.

The phase modulated energy may be repeated, amplified and/or multiplied in frequency in other stages such as I in Figure 2 before it is radiated by antenna D .

Other modifications of Figure 5 can be suggested in which tubes F and F' may be of the screen grid type. Tubes D and D' could be replaced by four single anode tubes.

75 Another modification could be made by omit-

ting exciter E of Figure 5 and introducing feed-back energy into grid circuit G from the anode circuit in any suitable manner. This would make this stage B an oscillator. If grid circuit G has low power factor such as a resonant line or a quartz crystal changes in anode tank circuit reactance of stage B will produce frequency modulation.

I claim:

1. In a system for modulating the wavelength of wave energy in accordance with controlling potentials, a circuit tuned to resonance at the mean frequency of said wave energy, said circuit comprising inductive reactance in one branch and capacitive reactance in another branch, a variable impedance shunting a part only of the reactance in one of said branches, a second variable impedance shunting a part only of the reactance in the other of said branches, means for impressing wave energy on said circuit, means for deriving wave energy from said circuit and means for varying said impedances in accordance with controlling potentials.

2. In a system for modulating the phase of wave energy in accordance with signals, a circuit tuned to resonance at the mean frequency of said wave energy, said circuit comprising an inductive branch and a capacitive branch, said capacitive branch comprising capacities in series, a variable impedance shunting a portion of said capacitive branch, a variable impedance shunting a portion of said inductive branch, means for impressing wave energy on said circuit, means for deriving wave energy from said circuit and means for varying said impedances in opposite senses at signal frequency.

3. In a phase modulation system, an electron discharge device having an anode, a cathode, and a control grid, alternating current circuits connected between said control grid and cathode and between said anode and cathode, means for causing wave energy of the desired frequency to flow in said circuits, one of said circuits comprising parallel reactances and being resonant at the frequency of said wave energy, a variable impedance in shunt to a part only of one of said reactances, a variable impedance in shunt to a part only of the other of said reactances, and means for varying said impedances in displaced phase relation at signal frequency.

4. In a phase modulation system, an electron discharge device having an anode, a cathode, and a control grid, alternating current circuits connected between said control grid and cathode and between said anode and cathode, means for causing wave energy of the desired frequency to flow in said circuits, one of said circuits comprising parallel inductive and capacitive branches and being resonant at the frequency of said wave energy, a variable impedance in shunt to a part only of one of said branches, a variable impedance in shunt to a part only of the other of said branches, and means for varying said impedance in displaced phase relation at signal frequency.

5. In a phase modulation system, a plurality of electron discharge devices each having an anode, a cathode, and a control grid, alternating current circuits inter-connecting said control grids and cathodes and said anodes and cathodes, means for causing wave energy of the desired frequency to flow in said alternating current circuits, one of said alternating current circuits in-

cluding capacitive and inductive reactances in parallel and being parallel resonant at the frequency of said wave energy, a variable impedance connected in shunt to a part only of one of said reactances, a second variable impedance connected in shunt to a part only of the other of said resistances, and means for varying said impedances at signal frequency.

6. In a phase modulation system, a plurality of electron discharge devices each having an anode, a cathode, and a control grid, alternating current circuits inter-connecting said control grids and cathodes and said anodes and cathodes, means for causing wave energy of the desired frequency to flow in said alternating current circuits, one of said alternating current circuits including a capacitive branch and an inductive branch, a variable resistor connected in shunt to each of said branches, and means for varying said resistances in phase opposition at signal frequency.

7. In a phase modulation system, a plurality of electron discharge devices each having an anode, a cathode, and a control grid, alternating current circuits inter-connecting said control grids and cathodes, other alternating current circuits inter-connecting said anodes and cathodes, means for causing wave energy of the desired frequency to flow in said alternating current circuits, said other of said alternating current circuits including a capacitive branch and an inductive branch tuned to the mean frequency of said wave energy, a variable resistor connected

in shunt to each of said branches, and means for varying said resistances in phase opposition at signal frequency.

8. The method of modulating the wavelength of wave energy by means of a circuit comprising inductive and capacitive branches in parallel tuned to resonance at the mean frequency of said wave energy which includes the steps of, impressing said wave energy on said circuit, deriving wave energy from said circuit, impressing a resistive component on each leg of said circuit, and varying said resistive components in phase opposition at signal frequency, to thereby vary the reactive components of said circuit at signal frequency.

9. In a wave length modulation system, an electron discharge device having an anode, a cathode, and a control grid, alternating current circuits connected between said control grid and cathode and between said anode and cathode, means for causing wave energy of the desired frequency to flow in said circuits, the alternating current circuit between said anode and cathode comprising two parallel branches, an inductance in one of said branches, series capacities in the other of said branches, a variable impedance in shunt to a portion of said inductance, a variable impedance in shunt to one of said capacities, means for varying said impedances in opposition at signal frequency, and an auxiliary electrode in said tube between said control grid and anode for screening the former from the latter.

GEORGE LINDLEY USSELMAN.
